(57) **CLAIM**

The ornamental design for a search and landing light for an aircraft, as shown and described.

DESCRIPTION

FIG. 1 is a front and side perspective view of a search and landing light for an aircraft, showing our new design;

FIG. 2 is a rear and side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the search and landing light for an aircraft that form no part of the claimed design.
